UNITED STATES PATENT OFFICE

130,765

DESIGN FOR AN EMBROIDERED TEXTILE FABRIC OR SIMILAR ARTICLE

Jack Wiener, New York, N. Y.

Application April 26, 1941, Serial No. 100,625

Term of patent 3½ years

To all whom it may concern:

Be it known that I, Jack Wiener, a citizen of the United States of America, residing at 160 Riverside Drive, New York, New York, have invented a new, original, and ornamental Design for an Embroidered Textile Fabric or Similar Article, of which the following is a specification, reference being had to the accompanying drawing, forming a part thereof.

The figure is a plan view of an embroidered textile fabric showing my new design. The dot and dash lines on the drawing outline substantially the design unit which unit is repeated in regular succession as indicated by the extensions beyond the unit boundaries. The cross hatching (not shown throughout) represents a backing fabric to which the embroidery is applied.

I claim:

The ornamental design for an embroidered textile fabric or similar article, as shown and described.

JACK WIENER.
